RETRACTABLE COUPLER FOR PILOTS

Harry H. Wolfe, Columbus, Ohio, assignor to The Buckeye Steel Castings Company, Columbus, Ohio

Application July 22, 1946, Serial No. 685,333

9 Claims. (Cl. 213—4)

1

This invention relates to improvements in retractable couplers for use at an end of a diesel or steam locomotive.

Such a coupler combined with a pilot provides a streamlined front end for a locomotive and also serves as a safety feature, as a protruding coupler tends to contribute to locomotive derailment when a land vehicle is struck at a grade crossing. A projecting coupler tends to pierce and hold the vehicle over the tracks, making it possible for it to roll under the locomotive and cause a derailment. On the other hand, if a retractable coupler is combined with a smooth sloping front end of the locomotive, the construction will tend to lift the vehicle and throw it to one side of the tracks.

In my patent, 2,400,584, I have disclosed a construction to accomplish the desired objects, but in the present application, I am illustrating and describing a modification employing a tightlock coupler and draft gear, and the present construction differs from the one disclosed in said patent, in the following respects.

1. A tightlock coupler is used, which requires provision for vertical swivel of the coupler as well as horizontal swivel. This is accomplished by the use of a cylindrical gear pocket in the yoke. The central portion of the draft gear is also cylindrical which permits limited vertical swivel of the coupler and yoke as a unit.

2. A horizontal buffer cast integral with the pilot door and extending over the coupler to within about 2" of the pulling face of the knuckle, is employed. The buffer is used on locomotives in passenger train service for the platform buffers on the cars to strike against. The face of the buffer used is cast solid, although it is obvious resilient means could be used, such as a rubber block or a spring arrangement.

3. The rear draft lugs are cast integral with the pilot door but the front draft lugs are separate and removable, and are held in place by tapered wedges. By removing the two wedges, the spring coupler and yoke carrier, the coupler yoke and draft gear can be removed through the front opening.

4. The coupler operating rods are mounted on the pilot door and can be retracted with the coupler without disconnecting any parts.

My invention includes the various novel features of construction and arrangement of parts hereinabove more definitely specified, and illustrated in the accompanying drawings.

In the drawing:

Fig. 1 is a fragmentary front elevation of a pilot 55

2

provided with my improvements and with certain parts in vertical cross section and other parts removed to facilitate illustration.

Fig. 2 is a top plan view of the retractable coupler and door, partly in horizontal section.

Fig. 3 is a vertical sectional view of a detail taken on the line 3—3 of Fig. 2.

Fig. 4 is a vertical sectional view of a detail taken on the line 4—4 of Fig. 2.

10 Fig. 5 is a longitudinal vertical sectional view taken in general on the line 5—5 of Fig. 1 and showing the coupler and the yoke and the draft gear in side elevation.

15 Fig. 6 is a sectional view taken on the line 6—6 of Fig. 2.

Referring to the drawings, 1 designates a pilot having an opening or doorway 2 at its front leading to a recess within the pilot. In accordance with the invention, a door structure 3 is pivotally mounted in the pilot for movement about a vertical axis, and, for this purpose, a depending stud 4 is secured to the roof 4a of the pilot recess by means of bolts 4b or the like, and snugly engages a bearing 4c formed by a top wall 4d of the pilot door structure.

20 Immediately below the part 4, a hollow stud 5 is detachably secured by bolts 5a or the like, to the bottom wall 5b of the pilot, and the part 5 provides a bearing for a trunnion 5d extending downwardly from the door structure. It is obvious that a construction of this character will permit the ready attachment of the pilot door structure to the pilot or the removal of such structure therefrom.

25 A tightlock coupler 6 is connected to a yoke 7 having cylindrical surfaces 7a and 7b, struck from a center 7c for the purpose of permitting the coupler and yoke to turn about the axis 7c. The arcuate surfaces 7a and 7b permit the coupler to angle vertically. The coupler is connected to the front end of the yoke by a vertical pin 8, which allows the coupler to pivot about the axis of the pin.

30 35 A draft gear 9 having a cylindrical central portion to cooperate with the surfaces 7a and 7b of the yoke, extends through the latter for cooperation with front and rear draft lugs, as will be explained later.

40 45 A shelf or protruding lip 10 projects from the bottom portion of the front of the yoke to form a supporting surface on which the portion 11 of the coupler shank slides laterally.

The front end portion of the yoke is supported by a spring carrier 12 secured to the door structure by bolts 12a or the like.

The draft gear cooperates with vertical rear draft lugs 13 integral with the side walls of the draft gear pocket of the pilot door structure. The draft gear also cooperates with front draft lugs 14 preferably of A-shape in horizontal section and each provided with a wedge pocket to receive a wedge pin 15 extending through the top and bottom portions of the door structure provided with the draft gear pocket, as shown in Figs. 4 and 6. Obviously, the removal of the front draft lugs will facilitate introduction of the yoke or draft gear into the pocket or the removal of these parts therefrom.

The pilot door structure has an unapertured web 16 arranged diametrically opposite the mouth of the pocket which receives the draft gear and yoke, and the web 16 when closing the opening 2, conforms to the shape of the front surface 17 of the pilot. The opposite portion of the door structure carries a horizontal projection 18 which extends over the coupler to provide an abutment for vestibule buffers on passenger cars when coupled to the locomotive. The buffer is used only when the coupler is in use, and it is, therefore, made to retract with the coupler.

The operating mechanism for the coupler is composed of handle shafts 19, pivotally mounted in brackets 20 and 21, fixedly arranged within the door structure. Rods 22 are hooked on to the coupler rotary operating levers at 23 (Fig. 1) and welded to connecting links 24. The latter have keyways 25 slidably engaging keys 26 extending lengthwise of the shafts 19 so that the parts 24 can slide along the shafts to accommodate coupler swivel. As the keys 26 are welded to the shafts 19, the rods 22 will be caused to rotate whenever the shafts 19 are turned. As may be seen from Fig. 3, this is accomplished by means of a handle 27 connected to an arm 19a fixed to shaft 19, and the handle, of course, extends through a hole 35 in the front 17a of the pilot door structure so that it may be readily manipulated by a trainman. It may be seen that the operating mechanism is all back of the front surface 17 of the pilot with the exception of the handle 27.

The coupler 6 is releasably retained in the extended position shown in Fig. 2 by locking means 36 shown in dotted lines at the upper right hand corner of Fig. 1. The details of such locking means are disclosed in the Wolfe Patent 2,400,534 which include a sliding bolt (not shown) adapted to enter a socket in the pilot and maintaining the door structure in the position shown in Fig. 2. The locking means prevents free rotation of the door structure and the coupler during movements of the locomotive.

When the coupler is to be retracted, it is manually shifted on its pivot 8 until the guard arm side of the coupler engages a wall 28 (Fig. 2) at one side of the coupler pocket. Such manual movement of the coupler may be made after the locking means is detached from the sleeve 37. Additional force applied to the coupler 6 will cause the door structure 3 to be rotated about the axis of the bearings 4c and 5. Further rotation of the door structure will bring the web portion 16 into a position closing the opening 2 at the front of the pilot recess. This web 16 conforms to the shape and curvature of the front surface 17 of the pilot and thereby provides an unapertured surface at the front of the locomotive devoid of any pockets or cavities.

From the foregoing, it is believed the construction, operation and advantages of my invention

may be readily understood and it is apparent that changes may be made in the details disclosed without departing from the spirit of the invention, as expressed in the following claims.

5. What I claim and desire to secure by Letters Patent is:

1. A locomotive pilot having an internal pocket and a doorway opening into the pocket at the front of the pilot, a door structure pivotally mounted in the pocket and having at one side thereof a wall for substantially completely closing said doorway, and at the opposite side thereof a similar wall for partially closing said doorway, said latter wall having a recess, a retractable coupler connected to the door structure and extending into the recess of the last-mentioned wall, and a substantially horizontal buffer projection rigidly united with the door structure arranged above the coupler and extending through the doorway opening when the coupler is in coupling position.

2. A locomotive pilot having an internal pocket and a doorway opening into the pocket at the front of the pilot, a door structure pivotally mounted in the pocket and having at one side thereof a wall for substantially completely closing said doorway, and at the opposite side thereof a similar wall for partially closing said doorway, said door structure having a recess therein, a retractable coupler connected to the door structure and extending into the recess, and coupler operating means mounted on the door structure to move therewith and be retracted with the coupler without disconnecting any parts.

3. A locomotive pilot having a doorway at the front thereof and a recess communicating with the doorway, a pilot door structure pivotally mounted in said recess, a coupler operatively connected to the pilot door structure and adapted to project through said doorway, and operating means for the coupler comprising a rock shaft mounted in the door structure, a handle for the rock shaft extending forwardly of the door structure, a member slidably along the shaft and keyed thereto for rotation therewith, and a rod fixedly connected to said member and operatively connected to the coupler.

4. A retractable coupler and door assembly for a railway vehicle comprising, a pilot having a recess therein open at the front of the pilot, a door structure mounted for movement in said recess, including a wall adapted to close the opening at the front of the pilot in one position of the door structure, a coupler secured to the door structure adapted to extend through the opening at the front of the pilot in another position of the door structure, and a buffer projection carried by the door structure above the coupler extending through the opening at the front of the pilot when the coupler is in an operative position.

5. A retractable coupler and door assembly for a railway vehicle comprising, a pilot having a recess therein open at the front of the pilot, a door structure mounted for movement in said recess, including a wall adapted to close the opening at the front of the pilot in one position of the door structure, a coupler secured to the door structure adapted to extend through the opening at the front of the pilot in another position of the door structure, a buffer projection integral with the door structure, said buffer projection being positioned above the coupler and extending through the opening at the front of the pilot when the door structure is in second position.

6. In a retractable coupler unit for a locomo-

tive, a pilot having a recess therein open at the front of the pilot, a door structure mounted for rotation within said recess, a wall carried by the door structure adapted in one position to close the opening at the front of the pilot, a coupler connected to the door structure for swinging movement relative thereto and adapted to extend through said opening in another position of the door structure, means including a shaft journalled for rotation on the door structure for operating the coupler, a second wall on the door structure, and means extending through the second wall for turning said shaft.

7. In a retractable coupler unit for a locomotive, a pilot having a recess therein open at the front of the pilot, a door structure mounted for rotation within said recess, a wall carried by the door structure adapted in one position to close the opening at the front of the pilot, a coupler connected to the door structure for swinging movement relative thereto and adapted to extend through said opening in another position of the door structure, a shaft journalled for rotation on the door structure, a second wall on the door structure, means extending through the second wall for turning said shaft, an elongated key carried by said shaft, a link slideable on said shaft and restrained against relative rotation thereon by said key, and a coupler operating rod secured to said link and connected to the coupler to move with the coupler.

8. In a retractable coupler and door assembly for a railway vehicle, a pilot having a recess therein open at the front of the pilot, a door structure pivotally mounted in said recess and having a wall at one side thereof for substantially closing said recess, said door structure having a cavity therein, rear draft lugs carried by the door structure within said cavity, front draft lugs

having holes therein, tapered pins extending into said holes detachably securing the front draft lugs to the door structure, a draft gear assembly within the cavity cooperating with the front and rear draft lugs, and a coupler operatively connected to the draft gear assembly.

9. In a retractable coupler and door assembly for a locomotive, a pilot having a recess therein open at the front thereof, a door structure mounted for movement in said recess, a wall carried by the door structure for closing the opening at the front of the pilot in one position of the door structure, said door structure having a cavity therein, rear draft lugs integral with the door structure within said cavity, front draft lugs having vertically disposed wedge-shaped holes therein, wedge-shaped pins extending through said holes and into apertures in the door structure, a draft gear assembly within the pocket operatively associated with said lugs, and a coupler connected to said draft gear assembly.
